DESIGN FOR A DRESS ORNAMENT

Herman Wapnick, Brooklyn, N. Y.

Application July 27, 1946, Serial No. 132,017

Term of patent 3½ years

(Cl. D45—19)

To all whom it may concern:

Be it known that I, Herman Wapnick, a citizen of the United States, residing at Brooklyn, New York, in the county of Kings and State of New York, have invented a new, original, and ornamental Design for a Dress Ornament, of which the following is a specification, reference being had to the accompanying drawing, forming a part thereof.

In the drawing:

Fig. 1 is a front elevational view of a dress ornament, showing my new design; and

Fig. 2 is a side elevational view of the same.

I claim:

The ornamental design for a dress ornament, as shown.

HERMAN WAPNICK.
